GERMICIDAL DETERGENT

Halvor O. Halvorson, and John L. Wilson, St. Paul, and Erling J. Ordal, Minneapolis, Minn., assignors to Economics Laboratory Inc., St. Paul, Minn., a corporation of Delaware

No Drawing. Application May 8, 1935,
Serial No. 20,508

4 Claims. (Cl. 167—17)

This invention relates to new germicidal detergent compositions.

The new compositions contain alkalies or buffer salts, soaps, and azochloramid, in such proportions that when, for example, a solution is made of the composition, containing from $\frac{1}{2}\%$ to 3% of the composition, the solution will be an effective germicidal detergent, and the soap and the azochloramid will each form only a small fraction of 1% of the solution.

Azochloramid is an abbreviated name for the compound $N - N - \text{dichloro-azodicarbonamidine}$, $\text{NH}_2(\text{NCl})\text{:C.N:N.C:}(\text{NCl})\text{.NH}_2$. This compound is known to have germicidal properties, but when used together with soap in solutions which are alkaline with suitable alkalies or buffer salts, the azochloramid and the soap appear to have a mutual activating action upon each other, or the azochloramid, which by itself is an excellent germicidal agent, is activated to a very considerable extent by the soap in such an alkaline solution.

It has been found that the compositions may contain alkalies which give a high alkalinity or pH value, and that the azochloramid is not rendered inactive by such high alkalinites, so that compositions can readily be made of high alkalinity, which is important from a detergent standpoint as well as from a bacteriological standpoint. The compositions are moreover effective as germicidal detergents at relatively low pH values. The range of pH values of the solutions of the new compositions may thus include low pH values of around 7 to 10 or 11, as well as higher pH values materially in excess thereof.

The buffer salts which are used in the new composition are alkaline salts or alkalies, such as carbonates, phosphates or silicates, etc., used in such amounts and proportions as will give to the final solution the desired pH value. Among such buffer salts may be mentioned sodium carbonate and bicarbonate, mono-sodium- and di-sodium phosphate, sodium silicates, etc.

In using these buffer salts, in making the new composition, the proper pH is obtained by a selection of the buffer salts employed which may, in some cases, be a single salt or salts of the same acid, such as sodium carbonate and bicarbonate, or salts of different acids, etc. For example, the proper pH may be obtained by the use of a mixture of various phosphates and carbonates, or various phosphates and silicates, or carbonates and silicates, or by mixtures of phosphates, carbonates and silicates, as well as by mixtures of various phosphates alone, or carbonates alone, or silicates alone. Similarly, other salts besides

phosphates, carbonates and silicates may be used to obtain the proper pH.

The particular salt or salts employed for obtaining the new compositions are best defined by the pH of the resulting solution rather than by the particular salts or combinations of salts employed, since the particular salt or mixtures of salts employed can readily be selected to give the desired pH value, e. g., within the range of from 7 to 12 or higher.

Different soaps can be used in the composition of the present invention, including ordinary soaps such as tallow soap, or resin soaps such as sodium resinate.

In general, the amount of soap employed, in proportion to the amount of buffer salts, will be such that the soap will be present to the extent of only a small percentage of 1% in the final solution, and the amount of azochloramid will also be only a small fraction of 1% of such a solution.

Solutions made from the new composition, in proportions and amounts such as those above mentioned, are excellent detergents and exhibit sufficient germicidal properties so that they can be used as germicides. In general, the solutions made with the new composition will contain from around $\frac{1}{2}\%$ to 3% of the composition.

The new composition is advantageously compounded and marketed in the form of a dry powder, containing the various ingredients in the form of an intimate and homogenous admixture, such that a definite weight of the powder can be used to give a solution of definite strength or proportions of the different ingredients. Such a dry mixture of the ingredients can be readily produced, handled, shipped and stored, and a definite amount measured out for use in producing germicidal detergent solutions.

In testing the solutions of the new composition, we have used the following test: The dry mixture, containing the ingredients of the composition, is made into a solution of from $\frac{1}{2}\%$ to 1% strength. To 5 cc. of this solution is added $\frac{1}{2}$ cc. of a 24 hour culture of the standard test organism, *Staphylococcus aureus* (Insecticide Board strain). Before the culture is added to the test solution, it is brought to the required temperature; the temperature we have used has been 37° C. or such other temperature as indicated. After the culture has been in the test solution for five minutes, a 4 mm. loopful is removed and added to a tube of molten agar at a temperature of 45° C. and the mixture is poured into a Petri plate. The plates are incubated for 48 hours, at the end

of which time a count is made of the colonies appearing on the plate. The number of organisms originally added to the test solution is in the neighborhood of five hundred millions (500,000,000). If no organisms are killed, the loopful removed will contain an excess of 10,000 organisms, and therefore the number of colonies appearing on the plates will be in excess of 10,000. If some of the organisms are killed, the number 10 of colonies appearing on the plates will be less than 10,000. In the data reported in the following examples the numbers indicate the colonies appearing on the test plate after 48 hours of incubation. Similar tests were made using *Eberthella typhi* (Hopkins strain.)

15 The invention will be illustrated by the following examples.

20 The composition was made of sodium resinate soap, azochloramid, and buffer salts, using equal 20 parts of sodium carbonate and sodium bicarbonate as the buffer salts to give a pH of 9.7 in a 1% solution of the composition, and using amounts of sodium resinate and of azochloramid indicated in the following table, which gives the results of 25 tests carried out at a temperature 37° C. with *Staphylococcus aureus* (24 hour culture):

30	Solution tested	Plate counts		25
		5 min.	10 min.	
35	1% buffer+0.1% sodium resinate	5,000	3,000	
	1% buffer+0.005% azochloramid	500	59	
	1% buffer+0.1% sodium resinate+0.005% azochloramid	5	1	
	1/80 phenol (as control)	0	0	
	1/90 phenol (as control)	100	0	

40 From this table it will be noted that the buffer salt and sodium resinate alone were not effective, while the effectiveness of the azochloramid was markedly increased by the presence of the sodium resinate in the alkaline solution. The two phenol 45 solutions included in the above table are given for purposes of comparison, as the control.

45 As further illustrative of the invention, tests were made in which azochloramid was used in different proportions with a buffer solution, and without sodium resinate, and in which sodium resinate was used with the buffer solution, without 50 the azochloramid, as well as tests in which both sodium resinate and azochloramid were used with the buffer salts. These tests were carried out at a temperature of 45° C. with a *Staphylococcus aureus* organism (24 hour culture), using a buffer 55 solution made up of equal parts of sodium carbonate and sodium bicarbonate which would give a pH of 9.7 in 1% solution. The following results were obtained:

60	Solution tested	Plate counts		65
		5 min.	10 min.	
65	1% buffer+0.004% azochloramid	28	0	
	"+0.002% azochloramid	100	15	
	"+0.001% azochloramid	1,000	200	
	"+0.0005% azochloramid	5,000	200	
	1% " "+0.1% sodium resinate	150	0	
	" "+0.1% sodium resinate+0.004% azochloramid	0	0	
70	" "+0.1% sodium resinate+0.002% azochloramid	0	0	
	" "+0.1% sodium resinate+0.001% azochloramid	15	0	
	" "+0.1% sodium resinate+0.0005% azochloramid	40	1	

75 From this table it will be seen that, while the

azochloramid and buffer salts showed a germicidal activity, this was markedly increased when sodium resinate was also present, and effective anti-septic or germicidal solutions were obtained with a strength of azochloramid which was ineffective 5 in the absence of the sodium resinate, thus showing the activating action of the sodium resinate upon the azochloramid, or the mutual activation of these substances by each other.

As further illustrating the invention, tests were 10 made with tallow soap, as the soap constituent of the composition, in comparison with solutions free from azochloramid, and solutions containing azochloramid but free from tallow soap. The tests were carried out at a temperature of 37° C. with 15 the same organism above referred to and with the use of a 1% solution of sodium silicate (Na₂SiO₃·5H₂O) giving a pH of about 12.3. The 20 solutions tested and the results obtained are indicated by the following table:

Solution tested	Plate counts		25
	5 min.	10 min.	
1% buffer	7,000	1,500	
1% buffer+0.01% tallow soap	2,000	300	
1% buffer+0.003% azochloramid	200	20	
1% buffer+0.01% tallow soap+0.003% azochloramid	100	0	
1/90 phenol (as control)	1	0	30
1/100 phenol (as control)	10	2	

From the foregoing examples it will be seen that the azochloramid is used in only small fractions of 1% of the final solution and that the soap is 35 also used in small fractions of 1% of the final solution, although in amounts considerably larger than the amounts of azochloramid. The main constituent of the composition, from a percentage basis, is the buffer salt, or mixture of buffer salts, which form, e. g., around 1% or 2% of the 40 final solution.

In preparing the new composition for the market, it is advantageously prepared in the form of a dry powder or mixture containing the different 45 ingredients in the proper proportions. Such a dry powder or mixture can be readily manufactured, stored and shipped, and can be readily used for detergent purposes, where a detergent 50 germicide is desired, merely by adding the composition to water in the proper proportions and using the resulting solution as a germicidal detergent.

While, in the above examples, only two specific 55 soaps are mentioned, it will be understood that other soaps can be used. The nature and amount of the buffer salt, or of the different buffer salts, used, can be varied, and the detergent action of the solution somewhat controlled thereby, as well as by the nature and amount of the soap used. It is one advantage of the present invention, as above mentioned, that a wide pH range 60 can be used without interfering with the effectiveness of the germicidal properties of the solution, so that high pH solutions can be produced 65 and used.

The new compositions are useful for many 70 purposes, as in hospitals or institutions, as well as in hotels and restaurants for dish-washing and other purposes, and in various industries such as the beverage and dairy industries where, for example, the washing and sterilizing of bottles and containers is important.

We claim:

1. A germicidal detergent composition comprising 75

ing buffer salts, soap, and azochloramid, said composition being soluble in water, and a solution made therefrom, and containing from $\frac{1}{2}\%$ to 3% of the composition, containing only a small fraction of 1% of the soap and azochloramid, the azochloramid being present in amounts insufficient to render such solution germicidal in the absence of the soap.

2. A germicidal detergent composition in the form of a dry mixture of buffer salts, soap and azochloramid, the composition being made up for the most part of buffer salts, and containing a relatively smaller amount of the azochloramid and of the soap, and the composition being adapted, when dissolved in water to form a solution containing from around $\frac{1}{2}\%$ to 3% of the composition, to give an active germicidal detergent composition, the azochloramid being present in amounts insufficient to render such solution germicidal in the absence of the soap.

3. A germicidal detergent composition in the form of a dry mixture of buffer salts, soap and

azochloramid, the composition being made up for the most part of buffer salts, and containing a relatively smaller amount of the soap, and a small amount of the azochloramid, such that when the composition is dissolved in water to 5 form a solution containing sufficient of the composition to give an effective detergent solution, the solution will be actively germicidal and the azochloramid will be present in an amount less than that required for the solution to be germicidal in the absence of the soap.

4. A germicidal detergent solution containing less than 3% of buffer salts, a fraction of 1% of a soap, and a small amount of azochloramid less than the amount normally soluble in distilled 15 water at the temperature of the solution, and less than that required to make the solution germicidal in the absence of the soap.
